UNITED STATES PATENT OFFICE

JEAN ALLEAS, OF EAST BOSTON, MASSACHUSETTS

FUEL ECONOMIZER FOR INTERNAL COMBUSTION ENGINES

Application filed May 31, 1929. Serial No. 367,216.

This invention relates to the art of fuel conservation, and to that class or those classes of devices used in connection with internal combustion engines generally, and more particularly in connection with internal combustion engines of motor vehicles, to effect economies in the costs of operation of engines of this character. Such devices may properly be termed, and are herein so termed fuel-economizers for internal combustion engines, thus differentiating and distinguishing them from devices designed and constructed to effect economies in the costs of operation of engines utilizing fuels in manners other than by internal combustion.

The principal object of this invention is to secure by its use conservation of fuel in the practical operation of internal combustion engines to an extent greater than has been realized heretofore. Another object of this invention is to secure by its use conservation of fuel in the practical operation of internal combustion engines of motor vehicles under a characteristic condition of use, i. e., during the descents of hills, to an extent greater than has been realized heretofore. Another object of this invention is the realization of these preceding objects by the employment of means of simplicity of design and construction and of inexpensiveness of manufacture and sale. Another object of this invention is the realization of these preceding objects without the introduction, concomitantly, of any disadvantages in operation of internal combustion engines. That other desirable results less readily definable are realized by the use of this invention is demonstrated by the fact that the operation of internal combustion engines under variable load is more uniform when this invention is concomitantly used than when it is not used.

In order that the advantages resulting from the use of this invention may be fully appreciated, it seems desirable that brief consideration be given at this point to the operation of an internal combustion engine un-equipped with this invention. Brief consideration will be given subsequently to the operation of an internal combustion engine

equipped with this invention, and the effects of its use will be described in detail.

In the operation of the ordinary type of internal combustion engine, atmospheric air at ordinary temperatures is sucked into and through the carburetor, due to the creation by the action of the pistonheads in the cylinders, of a partial vacuum in the gaseous fuel passage connecting the carburetor with the gaseous fuel manifold. While in passage through the carburetor, the air becomes laden with a mist of liquid fuel by the aspiration of the liquid fuel through and from the foramen or foraminous structure of the carburetor into the air. This mist of liquid fuel is for the most part transformed by rapid evaporation into the gaseous state. This mixture of air and fuel, liquid and gaseous, now passes into and through the gaseous fuel passage, frequently termed the throttle pipe, and then into the gaseous fuel manifold, frequently termed the combustion mixture manifold. From the gaseous fuel manifold, this mixture of air and fuel, liquid and gaseous, passes through valves into the cylinders wherein it is compressed and fired, and the products of combustion are then discharged through the exhaust valves and the exhaust pipe into the atmosphere.

Most carburetors function by supplying a stream of liquid fuel under a substantially constant head through a foramen or foramen or foraminous structure to a current of air whose rate of flow is determined by the size of the air inlet of the carburetor. The size of the air inlet of the carburetor is variable, and is controlled by means actuated by the throttle lever and the accelerator pedal. The size or sizes of the foramen or foramen or foraminous structure of the carburetor is or are usually not variable. Such a liquid fuel mixing device yields a mixture of air and fuel, liquid and gaseous, of a relatively constant composition, not greatly dependent upon the rate at which the mixture of air and fuel, liquid and gaseous, is supplied to the cylinders of the internal combustion engine. The liquid fuel supply system is initially adjusted in a permanent manner to permit the flow to the carburetor of liquid

fuel at a rate just sufficient to maintain the internal combustion engine idling, i. e., operating under no load except its own frictional load, when the rate at which the mixture of air and fuel, liquid and gaseous, being supplied to the cylinders of the combustion engine is the minimum rate, i. e., when the air inlet of the carburetor is of the minimum opening and the throttle lever is at its lowest position. The composition of the mixture of air and fuel, liquid and gaseous, which will be supplied to the cylinders of the internal combustion engine under all conditions of operation and at all rates of speed, is determined then, in a general way, by the initial adjustment of the rate of flow of liquid fuel to the carburetor. There is one way whereby successful operation of the internal combustion engine upon a lesser rate of flow of liquid fuel to the carburetor can be realized, and fuel thereby conserved. The preheating of air by the internal combustion engine exhaust before it is admitted to the carburetor, results in the elevation of the working temperature of the carburetor, insures more complete evaporation of the liquid fuel, and does permit the utilization of a finer adjustment of the rate of flow of liquid fuel to the carburetor. But this method of conserving fuel is effective only after the internal combustion engine has been in operation for a time sufficient for the generation of the heat required for the preheating of the air to have occurred, and difficulties are encountered in attempting to start a cold internal combustion engine upon a mixture of air and fuel, liquid and gaseous, of such a composition.

It has been found that the admission of air or other gas at ordinary or elevated temperatures into the gaseous fuel passage or into the gaseous fuel manifold of an internal combustion engine at any point or points subsequent to the carburetor is greatly effective in decreasing the rate of consumption of liquid fuel during its operation. While no attempt at a theoretical explanation of this phenomenon can be offered, it seems probable that under such conditions, the air or other gas acts as a diluent of the original mixture of air and fuel, liquid and gaseous, delivered by the carburetor, and materially aids in the evaporation of the remaining liquid fuel in the state of fine division.

The operation of internal combustion engines utilizing the diluted fuel mixtures formed as described in the preceding paragraph has been found to be very satisfactory, particularly at the higher speeds. By suitable means of regulation of the rate of admission of air or other gas at ordinary or elevated temperatures admitted into the gaseous fuel passage or into the gaseous fuel manifold of an internal combustion engine, the most economical gaseous fuel mixture for

the production of a given speed and a given power can be determined, produced, and delivered to the cylinders of the internal combustion engine for consumption. By suitable means of regulation of the rate of admission of air or other gas at ordinary or elevated temperatures admitted into the gaseous fuel passage or into the gaseous fuel manifold of an internal combustion engine, the compositions of the mixture of air and fuel delivered to the cylinders of the internal combustion engine can be varied from the composition of the mixture of air and fuel, liquid and gaseous, as delivered by the carburetor, to a content in fuel of substantially zero.

In most States, if not in all, it is an unlawful act for anyone to coast a motor vehicle down a hill, i. e., for anyone to allow a motor vehicle to travel down a hill with gears unmched or the clutch out. But when a motor vehicle travels down a hill with the gears meshed and the clutch engaged, the internal combustion engine is compelled to operate, i. e., to turn over, even though it may not only be generating no power, but may even be exerting some braking action upon the motor vehicle. Under such conditions, the internal combustion engine may be said to be working under a negative load. Though the throttle lever be set at its lowest point, and the ignition be switched off, a mixture of air and fuel, liquid and gaseous, will be delivered to the cylinders of the internal combustion engine, will be discharged through the exhaust valves and exhaust pipe, and will thereby be wasted. Such a waste of fuel can be completely prevented only by either disconnecting the carburetor from the gaseous fuel passage, or by disconnecting the liquid fuel line from the carburetor. Such a waste of fuel can be substantially prevented by the use of the present invention.

For the purpose of conserving fuel in the operation of internal combustion engines under steady, variable, or negative loads, one of the many possible forms of this invention, as applied to an internal combustion engine for motor vehicles is here offered and described in detail upon reference to the accompanying drawings in which

Figure 1 is a vertical section on the line 1, 1, of Figure 2,

Figure 2 is a vertical section on the line 2, 2, of Figure 1,

Figure 3 is a detailed view in perspective, of those parts of the invention which serve to govern the amount of air or other gas at ordinary or elevated temperatures admitted into the gaseous fuel passage or into the gaseous fuel manifold of the internal combustion engine, while

Figure 4 is a detailed vertical view of the invention as a whole, showing the means of actuation of the controlling device illustrat-

ed in the three preceding figures, means of preheating air, and a portion of the internal combustion engine, and Figure 5 is a schematic vertical view of an automobile chassis showing the invention directly connected to the gaseous fuel passage of the internal combustion engine at a point intermediate the gaseous fuel manifold and the carburetor, and showing also the means of actuation of the invention directly connected to the means of actuation of the carburetor.

Similar figures refer to similar parts throughout the five figures.

The circular disc 1, mounted upon the stem 2, turning freely in simple bearings in the valve body 10, constitutes with the valve body 10, a butterfly valve ensemble. This butterfly valve is actuated by the butterfly valve lever 9, attached to the stem 2, and the butterfly valve actuating rod 24, provided at its upper end with notches 25 which engage with the catch 27 set into the dashboard 26, of the motor vehicle. Integral with the butterfly valve lever 9 is the butterfly valve lever adjusting arm 14 provided with an adjusting screw 13, which in coaction with the valve body stop 12 serves to determine the maximum extent to which the butterfly valve can be opened. This portion of the invention may 30 be termed the coasting valve and consists broadly of a means of coarse regulation of the rate of admission of air or other gas at ordinary or elevated temperatures into the gaseous fuel passage or into the gaseous fuel 35 manifold of the internal combustion engine, together with a means of its actuation.

The butterfly valve body 10 is provided with a bypass 3, through which the rate of passage of air or other gas at ordinary or elevated temperatures is controlled by the bypass valve plug 4, provided with a bypass valve passage 15. The bypass valve plug 4, slightly tapering in form is retained snitgly in its seat by the bypass valve washer 16 and locknut 17. The bypass valve plug 4 is actuated by the bypass valve plug lever 5, which in turn is actuated by the accelerator pedal 34, acting through the bypass valve plug actuating rod 28, and the semi-rigid connection, 45 composed of the stop 29 upon the bypass valve plug actuating rod 28, the spring 30, the adjusted locknut 31, and the link 32, rigidly attached to the accelerator adjusting rod 33, but sliding freely upon the bypass valve plug 50 actuating rod 28. The operation of the bypass valve plug actuating rod spring 30, and the accelerator pedal retaining spring 35, which reacts upon the motor vehicle floor board 36, serves to maintain the bypass valve 55 closed when the accelerator pedal 34, is not in use. Integral with the bypass valve lever 5, is the bypass valve lever adjusting arm, 7, provided with an adjusting screw 8, which in coaction with the valve body acting at 6 as a stop, serves to determine the maximum

extent to which the bypass valve can be opened when the accelerator pedal is completely depressed. This portion of the invention may be termed the regular duty valve, and consists broadly of a means of fine regulation of the rate of admission of air or other gas at ordinary or elevated temperatures into the gaseous fuel passage or into the gaseous fuel manifold of the internal combustion engine, together with a means of its actuation, which is a function of the movement of the accelerator pedal, and hence at the rate at which air is admitted into the carburetor.

This controlling device consisting of the valves and their means of actuation, is connected at the exit orifice of the valve body to a nipple 19, venting into the gaseous fuel passage of the internal combustion engine at a point subsequent to the carburetor, and in this case, into the throttle pipe 18, which 70 serves as the gaseous fuel passage connecting the carburetor with the gaseous fuel manifold. The entrance orifice of the valve body is provided with an intake pipe connected with the air intake heater pipe 21, which surrounds the exhaust pipe 22, and which is supported thereupon, and spaced therefrom by the supporting lugs 23, forming thereby 75 a manifold for preheating the air taken into the intake pipe 20.

The operation of this form of the invention under various conditions of use is as follows:

During travel upon substantially level roads of the motor vehicle, the coasting valve 80 remains fixed: either closed or partly opened. When the accelerator pedal 34 is undepressed, as when the engine is idling, the bypass valve is just closed. The adjusting nut 31 is turned up until it makes contact 85 with the link 32. The spring 30 is now compressed between stop 29 and link 32. Upon depressing the accelerator pedal 34, force is applied through the spring 30, the stop 29, and the rod 28 to the lever 5, the bypass valve 90 is thereby opened, and air is permitted to pass through the stove 21, 22, 23, the air intake pipe 20, the bypass valve 3, 15, and connecting nipple 19, into the gaseous fuel 95 passage 18. When the bypass valve has been 100 opened as far as is permitted by the coaction of the adjusting screw and the stop 8, 6, further depression of the accelerator pedal 34 105 serves only to compress the spring 30.

During the descent of a hill by the motor vehicle, when otherwise the passage of air through the carburetor would entrain fuel, and thereby waste it, use for the coasting valve is indicated. This valve is then opened 110 to its fullest extent by the use of the butterfly valve actuating rod 24, worked at the motor vehicle dash board 26 by the operator of the motor vehicle. By far the greater portion of air or other gas drawn into the gaseous fuel 115 passage and through the cylinders of the in-

ternal combustion engine enters through the stove, the intake pipe, and the butterfly valve. The portion of air drawn into the gaseous fuel passage by way of the carburetor is insignificant, and the quantity of fuel lost in this manner is correspondingly insignificant. Even during travel upon substantially level roads, a judicious adjustment of the coasting valve will be found to result in the conservation of appreciable amounts of fuel, with little if any diminution of power.

While the foregoing description and outline of the nature and mode of operation of this invention, together with the accompanying drawings constitute a preferred embodiment of the invention, it is to be understood that this invention may be variously embodied with reference both to internal combustion engines of motor vehicles, and to stationary internal combustion engines. It is therefore to be limited only as it is claimed. Several of the points of this invention as embodied otherwise than in the mode in which they are here embodied may be considered. The entrance or admission of air or other gas into the gaseous fuel passage need not be effected at the throttle pipe, but may be effected at any point or points subsequent to the carburetor. The valve ensemble may be replaced by separate valves and separate intake pipes and preheaters. The valves may be of such types as will permit the fine and coarse regulation of the rate of admission of air or other gas at ordinary or elevated temperatures into the gaseous fuel passage or into the gaseous fuel manifold. The actuation of the means of coarse regulation may be automatic, instead of manual, and independent means, as for example by the use of a pendulum regulator, or by the coaction of a governor operated by the engine and a trip lever functioning during the non-use of the accelerator pedal. The preheating of the air admitted into the gaseous fuel passage or into the gaseous fuel manifold may be accomplished by any mode of preheating in which the heat consumed therein was produced directly or indirectly by the internal combustion engine. The gas admitted into the gaseous fuel passage or into the gaseous fuel manifold need not be air, but may be exhaust gas taken directly from the exhaust pipe. The semi-rigid connection of the bypass valve with the accelerator pedal may be replaced by any other semi-rigid type of connection functioning similarly.

Having thus described the invention, I claim:

1. In combination with an internal combustion engine having a carburetor and an intake manifold, an auxiliary inlet passage for supplying preheated air to the said manifold above the carburetor, and a plurality of independent means for regulating the said preheated air supply consisting of the com-

bination of a valve means of coarse regulation actuated manually and of a valve means of fine regulation actuated by the carburetor pedal through connection therewith permitting and controlling the bypassing of the preheated air around and past the valve means of coarse regulation. 70

2. In combination with an internal combustion engine having a carburetor and an intake manifold, an auxiliary inlet passage for supplying preheated air to the said manifold above the carburetor, and a plurality of independent means for regulating the said preheated air supply consisting of the combination of a valve means of coarse regulation actuated manually and of a valve means of fine regulation actuated by the carburetor pedal through semi-rigid connection therewith permitting and controlling the bypassing of the preheated air around and past the valve means of coarse regulation. 75

3. In combination with an internal combustion engine having a carburetor and an intake manifold, an auxiliary inlet passage for supplying preheated air to the said manifold above the carburetor, and a plurality of independent means for regulating the said preheated air supply consisting of the combination en bloc of a valve means of coarse regulation actuated manually and of a valve means of fine regulation actuated by the carburetor pedal through semi-rigid connection therewith permitting and controlling the bypassing of the preheated air around and past the valve means of coarse regulation. 80

4. In combination with an internal combustion engine having a carburetor and an intake manifold, an auxiliary inlet passage for supplying preheated air to the said manifold above the carburetor, and a plurality of independent means for regulating the said preheated air supply consisting of the combination en bloc of a butterfly valve actuated manually and of a bypass valve actuated by the carburetor pedal through semi-rigid connection therewith permitting and controlling sensitively the bypassing of the preheated air around and past the butterfly valve. 105

5. In combination with an internal combustion engine having a carburetor and an intake manifold, an auxiliary inlet passage for supplying preheated air to the said manifold above the carburetor, and a plurality of independent means for regulating the said preheated air supply consisting of the combination en bloc of a butterfly valve actuated manually and of a ground key cock actuated by the carburetor pedal through semi-rigid connection therewith permitting and controlling sensitively the bypassing of the preheated air around and past the butterfly valve. 110

6. In combination with an internal combustion engine having a carburetor and an intake manifold, an auxiliary inlet passage for supplying preheated air to the said manifold 115

above the carburetor, a plurality of independent means for regulating the said pre-heated air supply consisting of the combination en bloc of a butterfly valve actuated 5 manually and of a ground key cock actuated by the carburetor pedal through semi-rigid connection therewith permitting and controlling sensitively the bypassing of the pre-heated air around and past the butterfly 10 valve, a preheating stove of which the exhaust pipe constitutes the heating element, and an intake pipe connecting the said preheating stove with the said plurality of independent means for regulating the said preheated air 15 supply.

In testimony whereof, I affix my signature.
JEAN ALLEAS.
